Dwight F. Walker,
INVENTOR

BY *John G. Nederhuis,*

ATTORNEY.

UNITED STATES PATENT OFFICE.

DWIGHT F. WALKER, OF PHILADELPHIA, PENNSYLVANIA.

PAPER HOLDER AND CUTTER.

SPECIFICATION forming part of Letters Patent No. 510,742, dated December 12, 1893.

Application filed July 12, 1893. Serial No. 480,223. (No model.)

To all whom it may concern:

Be it known that I, DWIGHT F. WALKER, a citizen of the United States, residing in the city and county of Philadelphia, State of Pennsylvania, have invented a new and useful Improvement in Paper Holders and Cutters, which improvement is fully set forth in the following specification and accompanying drawings.

10 My invention relates to improvements in paper holders and cutters, and consists of a head which is adapted to form a weight, a cutter and a feed or device for unrolling the paper as will be hereinafter set forth.

15 Figure 1 represents a front view of a paper holder and cutter embodying my invention. Fig. 2 represents a transverse vertical section thereof on line x, x , Fig. 1. Fig. 3 represents a view of a detached portion thereof. 20 Fig. 4 represents a transverse vertical section showing the head in a different position from that in Figs. 1 and 2. Fig. 5 represents a horizontal section of a portion on line y, y , Fig. 2. Fig. 6 represents a side elevation of 25 a portion of a modification. Fig. 7 represents a side elevation thereof.

Similar letters of reference indicate corresponding parts in the several figures.

Referring to the drawings: A designates a 30 base with standards B rising therefrom.

C designates a roller whose journals D are mounted on the standards B in recesses E therein.

35 F designates a gravitating head which is provided with journals or gudgeons G, and constructed of quadrilateral, prismatic or other suitable shape in cross section, with cutting edges H at the angles or corners thereof, said gudgeons G being fitted in either of 40 the recesses J in the standards B, it being noticed that the recesses J diverge from the recesses E, and that access is had to either of the recesses through the grooves K which are interposed between the recesses E and J.

45 On the roller C is the paper to be held and cut, it being noticed that the head F is placed in position by introducing the gudgeons G through the recesses K into either of the recesses J, and then raising the head, after 50 which the roll is introduced and its journals

seated in the recesses E, and the head is then dropped or placed on the roll of paper, as shown in Fig. 2.

The operation is as follows: When it is desired to cut off a piece of paper, the latter is 55 pressed against the adjacent edge of the head F, and run across the same after the manner of a paper holder. Should the edge of the portion of the paper remaining on the roll be beneath, or be covered by the head, whereby 60 it is inconvenient of access, the head is rotated, whereby its edges take hold of the paper and feed the same forward, as will be seen in Fig. 4, thus presenting sufficient paper to be grasped by the hand and further 65 unrolled. As the roll of paper decreases in diameter, the head F descends, and so exerts its weight upon the roll, thus preventing the latter from improperly unrolling and causing the paper to be severed or cut clean and 70 sharp, it being run across the edge of the head.

Owing to the diverging grooves or recesses J, and the ability to introduce the gudgeons of the head F in either of the same, the head 75 may be made operative from the right or left, according to the location and disposition of the device.

In Figs. 6 and 7, I show the roller and head mounted on hangers K', the same having diverging recesses L for the head, bottom recesses M for the roller, and intermediate grooves N for the introduction of the respective gudgeons and journals into said recesses L and M. The hangers K' may be connected 80 with a counter, table or other suitable place of suspension.

Having thus described my invention, what I claim as new, and desire to secure by Letters Patent, is—

1. In a paper holder and cutter, a roller for the paper, in combination with a rotatable head vertically movable in its journal bearing and adapted to bear on the paper on said roller, and having cutting edges, substantially 85 as described.

2. A paper holder having standards with recesses therein, a roller journaled in said recesses, and a rotatable cutter journaled above said roller in continuations of said recesses, 90

100

said cutter normally resting on said roller, said parts being combined substantially as described.

3. A roller, a head, and a support having 5 recesses for the journals of said roller, and diverging recesses for the gudgeons of said head, said head being rotatable and formed with a cutting edge or edges, said parts being combined substantially as described.
- 10 4. A paper holder having standards with recesses therein, a roller and a cutter, the latter being provided with gudgeons which are mounted above said roller in recesses continuous of those which receive said gudgeons,

15 said parts being combined substantially as described.

5. In a paper holder and cutter, a roller and a head in combination with a support for said roller and head, said support having recesses for the journals of the roller, diverging recesses for the gudgeons of the head, and intermediate grooves for introducing said journals and gudgeons into the respective recesses, substantially as described.

DWIGHT F. WALKER.
